UNITED STATES PATENT OFFICE.

ALBERT H. VOSS, OF DAVENPORT, IOWA.

TRUCK-FRAME AND BOLSTER.

1,240,270.

Specification of Letters Patent. Patented Sept. 18, 1917.

Application filed June 1, 1916. Serial No. 101,147.

To all whom it may concern:

Be it known that I, ALBERT H. Voss, a citizen of the United States, residing at Davenport, in the county of Scott and State 5 of Iowa, have invented certain new and useful Improvements in Improved Truck-Frames and Bolsters, of which the following is a specification.

This invention comprehends new and useful 10 improvements in railway truck frames and bolsters; and it contemplates, primarily, the provision of a novel form of truck frame which, by reason of its peculiar construction, may be arranged to support and coöperate 15 with the bolster, while the latter is arranged so as to compensate for the traffic shocks incident to the operation of the car or other structure upon which the device is carried.

A further object of my invention is to 20 provide a device of the type in question that is extremely simple in construction, strong and durable, and highly practical from both the standpoint of the manufacturer and the standpoint of the user; and 25 which, it is believed, may be manufactured at comparatively low cost.

Various other objects and advantages will 30 become apparent during the continuance of the following description.

These objects are accomplished by such 35 means as are shown in their preferred form in the accompanying drawings, described in the following specification and then more specifically pointed out in the appended

claims.

In the accompanying drawings, wherein like characters designate like parts throughout the several views:—

Figure 1 is a view in plan of my improved 40 truck frame and bolster, showing the same as in their preferred embodiment;

Fig. 2 is a view in side elevation showing the truck frame more in detail;

Fig. 3 is a fragmentary view showing 45 more clearly the relative position of the end of the bolster with respect to the truck frame;

Fig. 4 is a cross sectional view taken on line 4—4 of Fig. 2;

Fig. 5 is a view in cross section taken on line 5—5 of Fig. 2;

Fig. 6 is a view in cross section taken on line 6—6 of Fig. 2;

Fig. 7 is a view in detail of the improved 55 bolster;

Fig. 8 is a view in perspective of an improved carrying plate that is associated with the bolster;

Fig. 9 is a view in perspective of an improved bearing or boxing that coöperates 60 with the bolster;

Fig. 10 is a view in perspective showing in detail an improved connecting member that is employed as shown in Fig. 3.

Fig. 11 is a detail view of one of the 65 fulcrum castings also illustrated in Figs. 1 and 7.

Fig. 12 is a detail view illustrating one of the connection chains and links to be associated with the elements 48 and 49 70 illustrated in Fig. 7.

In the present embodiment, 10 designates the truck frame, of my invention, in its entirety, while the numeral 11 designates the bolster. Since the respective truck frames 75 that are usually employed in connection with a bolster of the type shown are of substantially the same configuration, and construction, only one of such frames will be herein described in detail.

Referring firstly to the truck frame, 12 designates the skeleton body portion thereof that is preferably formed of cast metal and hollowed out a greater portion of its longitudinal extent in order to provide an open, 80 inexpensive, yet durable structure. Body 12 has located therein, a transverse partition 13 (refer to Fig. 5) the same terminating approximately halfway between the top and bottom sides of the body member, and 85 having a cross slot 14 provided therein, as illustrated.

A depending enlargement 16 is located on the under face of body member 12, substantially midway its ends, said enlargement having 90 provided therein, suitable disposed cut outs 17 (refer to Fig. 4) that accommodate certain coöperating parts of the device, subsequently described. By reason of the construction above elucidated, it is obvious that 100 the body member 12 may be cast integral with enlargement 15, although it is of course to be understood that I do not limit myself to the specific arrangement shown. Body member 12, has located at its respective 105 ends, vertically alined branches 17 and 18 respectively, between which may be accommodated a journal boxing or the like, as subsequently described, said branches being 110 connected through the instrumentality of

removable bolts, or the like fastening members, as at 19, whereby they may be drawn together sufficiently to grip the journal boxing or other structure engaged. Although 5 not limiting myself in any way to the construction shown, it may be advisable to cut away the upper branch 17 as at 20, in order to accommodate the head of bolts 19. Other fastening members, such as shown at 21, 10 may be associated with branch members 18, as shown in Fig. 2, in order to securely retain the same in place.

The intermediate portion of body member 12 has located therein, a transverse opening 15 22 that is substantially aligned with partition member 13 above referred to, the said opening being designed to receive one end of the bolster 11. Bolster 11, like truck frame 10, is preferably constructed of 20 cast metal or of an approximately similar construction, the ends thereof being slightly reduced as shown in Fig. 3 whereby they may be readily accommodated in the openings 22 of the truck frame, as previously 25 pointed out. Adjacent one end, bolster 11 is provided with spaced bearings 23 and 24, between which is provided a socket 25 for reception of boxing 26 that is substantially U-shaped in cross section, as in Fig. 9. Subsequent 30 to the arrangement of boxing 26, in position, between bearings 23 and 24, plate 28, such as shown in detail in Fig. 8, may be engaged with the boxing as in Fig. 3, and a bolt or other securing pivot 29 passed through the said bearings, boxing 35 and plate, in order to firmly secure the relative parts in position. When thus secured in place, carrying plate 28 projects into slot 14 of partition 13 above referred to, and also 40 projects to each side of the said partition 13, as shown in Fig. 5. Socket members 30 may now be pivotally connected to the respective end portions of plate 28 by means of their respective pairs of spaced bearings 31 and 45 fastening members or pivots 32, subsequent to which cushioning springs 33, preferably of the heavy duty type, may be positioned in sockets or spring seats 17 of the truck frame so as to engage with socket members 30 in 50 the manner clearly shown in Fig. 4. Consequently, it will be recognized that bolster 11 will be yieldingly supported with respect to the truck frame; springs 33 compensating for the traffic shocks transmitted to the 55 truck frame from the respective axles 34 and wheels 35.

In order to connect the truck frames in pairs and preclude the possibility of lateral movement thereof relative to one another, 60 during operation, I preferably equip each frame with an outstanding lug or bearing portion 36 which carries at its free terminal, an upstanding lip 37. A connecting plate 39 is then employed (see Fig. 10), the said 65 connecting plate having enlargements 40 at

each end, to ride upon the said bearings 36, in the manner illustrated in Fig. 3. After connecting plate has been arranged in position, a bolt 41 or other suitable fastening member may be passed through the respective enlargements and the bearings 36 in order to insure an efficient connection therebetween. 70

As will be noted, upon reference to Fig. 1, I provide truck frame 10 with suitably spaced hooks or bearing portions 42, in order to facilitate the connecting of the truck frame with the ordinary brake beam (not shown) by means of the usual chains. These hook portions are preferably of a 80 nature that will permit of the quick and easy removal or attachment of the connecting chain, in order to increase the general convenience of the device. 85

I also provide the bolster 11 with an improved fulcrum casting, (see Fig. 7), the same consisting of a bearing portion 43, which carries right angularly disposed flanges 44 and 45, for attachment to the respective side and top walls of the bolster, 90 as illustrated. Bearing portion 43 is also provided with a through opening 46. Bolts 47 may also be utilized for retaining this bracket in position. 95

From the above, it will be recognized that 100 while the pairs of truck frames serve to efficiently connect and coöperate with the axles 34 which are, of course, of conventional form, it will also be appreciated that the said truck frames provide an efficient support for the bolster, and permit of the introduction of means thereinto to yieldingly support the bolster and thus compensate for traffic shocks which would otherwise be conveyed thereto. Truck frames 10 are connected by means of plate 39, shown in detail in Fig. 10, while the bolster 11 is free to move vertically therein, during operation of the car or other structure, upon which the device is used. 110

In reducing my invention to practice I find that the form referred to herein as the most practical and preferred embodiment is the most efficient, but realizing that certain conditions will necessarily vary in concurrence with the adoption of my device, I desire to emphasize the fact that various minor changes in the details of construction and in the proportion of parts may be resorted to when required without sacrificing any of 115 the advantages of my invention, as defined in the appended claims. 120

Having thus fully described my invention, what I claim as new and desire to secure by Letters Patent is:— 125

1. The combination of a truck frame member having a socketed portion and a slotted partition within the socket thereof, a bolster having one end disposed above said partition, a member extending through the slot of 130

5 said partition and supporting one end of
said bolster, and means mounted in the socketed
portion and at opposite sides of said
partition for yieldingly supporting said
member.

10 2. The combination of a truck frame member
provided with a pair of spring seats,
vertical guiding elements between said spring
seats, a supporting member extending be-
tween the said vertical guiding elements,
spring seat elements connected to the respec-
tive ends of said supporting member, a bol-
ster having one of its ends associated with
said supporting member, and springs coop-
erating with the first said spring seat and
the second said spring seat and with said
supporting member for yieldingly supporting
one end of said bolster.

15 3. In a device of the character described,
the combination with a truck frame member
including a centrally located socketed por-
tion and an opening communicating with
said socketed portion, of a bolster having
one end disposed in said opening, a plate
20 carried by said bolster and having its ends
projecting laterally thereof within the socketed
portion of said truck frame member,
members pivotally mounted at the end por-
tions of said plate, and yieldable means in-
30 terposed between said members and the face
of the socketed portion of said truck frame
member to yieldingly support said bolster,
substantially as described.

35 4. In a device of the character described,
a truck frame member consisting of a skele-
ton body having a centrally located socketed
portion, and a partition in said socketed por-
tion, said partition being slotted trans-
versely, said truck frame member being pro-
40 vided with an opening above the aforesaid
socketed portion; in combination with a
bolster having one end disposed in said open-
ing, a plate pivotally mounted on said bol-
ster and operating in the slotted portion of
45 said partition, members pivotally mounted
adjacent the ends of said plate, and coil
springs interposed between the base of the
socketed portion of said truck frame mem-
ber and said last mentioned members, to

yieldingly support said bolster, substantially 50
as described.

5. In a device of the character described,
a truck frame member comprising a skeleton
body having a centrally located socketed
portion, and a partition extending trans-
versely of the socketed portion and having a
transverse slot intermediate its ends, said
truck frame member having an opening
therein above and in alignment with said
partition; in combination with a bolster 60
having one end passed into said opening, a
plate pivotally mounted at the end of said
bolster and operating in the slot of said par-
tition, members pivotally mounted at the re-
spective free terminals of said plates and
disposed at each side of said partition, and
coil springs interposed between said last
mentioned members and the base of the sock-
eted portion of said truck frame member,
thereby providing cushions for said bolster. 70

6. In a device of the character described,
a truck frame member comprising a body
having a centrally located socketed portion,
and a partition transversely disposed in said
socketed portion and having an interme-
diate transverse slot, said truck frame mem-
ber having an opening therein above and
in alignment with said partition; the com-
bination with a bolster having one end in
said opening, a plate pivotally connected in-
termediate its ends with said bolster and
operating in the slot of said partition, mem-
bers pivotally mounted on said plate adja-
cent its respective free terminals, and coil
springs interposed between said last men-
tioned members and the base of said sock-
eted portion; whereby said bolster will be
cushioned both upon movement vertically
with respect to the truck frame member and
slight turning movement with respect 90
thereto.

In testimony whereof I affix my signature
in presence of two witnesses.
